UNITED STATES PATENT OFFICE.

CARL WINKLER, OF BERN, SWITZERLAND.

CORE FOR MOLDS FOR CASTING CURVED STEREOPLATES.

Application filed December 9, 1926, Serial No. 153,674, and in Germany December 31, 1925.

Experience shows that the molds used for casting curved stereo-plates cool down better at the ends than in the middle. In order to obtain a more uniform temperature of the mold, the present invention provides that thin ribs, inside the core, are so arranged that a better cooling effect is obtained in the middle of the mold than at the ends. For this purpose the ribs can be placed closer together towards the middle of the core; they can also have a thinner section and a larger surface.

Plates cast in a mold having a core of this kind are more accurate, without requiring boring, and they also produce better printing, and need much less make ready.

In the drawing the core of a mold for curved stereo-plates, constructed according to the invention, is shown by way of example, Fig. 1 being a longitudinal section on the line A—B in Fig. 2, and Fig. 2 a section on the line C—D in Fig. 1.

The core has the usual shape and it is provided with a cooling jacket *a* in which water enters at *b*, leaving at *c*. This water comes into contact with the ribs *e* on the inside of the mold wall *d*, and these ribs are nearer together in the middle of the length than at both ends. The ribs *e*, in the example shown, all have the same section; they can however differ in this respect.

What I claim and desire to secure by Letters Patent of the United States is:

In a core for a mold for casting curved stereo-plates, the combination of a water jacket inside said core, and of ribs on the core wall projecting into said water jacket and arranged nearer together in the middle of the core than at the ends.

In testimony whereof I have signed my name to this specification.

CARL WINKLER.
